UNITED STATES PATENT OFFICE.

EARL G. SMITH AND ALBURT B. COMBS, OF PORTLAND, OREGON.

VALVE-FACING MACHINE.

Application filed May 31, 1923. Serial No. 642,470.

To all whom it may concern:

Be it hereby known that we, EARL G. SMITH and ALBURT B. COMBS, citizens of the United States, and residents of Portland, in the county of Multnomah and State of Oregon, have invented a new and useful Valve-Facing Machine, of which the following is a specification.

This invention relates more particularly to that class of machines which are used to face or reface valves and for internal combustion engines.

The objects of our invention are to provide an exceedingly simple and efficient valve facing machine which will easily and quickly face or reface a valve concentrically with the axis of the valve stem.

A further object is to provide a means for setting the attachment to grind valves at various angles.

A still further object is to provide a wheel truing attachment to be used in conjunction with the facing attachment, and which will keep the face of the grinding wheel parallel to its axis.

Still another object is to provide a special valve rotating crank which will permit a tight grip on the valve stem without having the parts thereof interfering with the valve stem supports.

These and other minor objects will be more fully explained in the specification following.

We accomplish these results in the manner set forth in the following specification and illustrated in the accompanying drawings, in which:

Figure 1 is a front elevation of our device with the grinding wheel outlined in the background and omitting the stand. Figure 2 is a partial end elevation of the valve rotating crank. Figure 3 is a section along the line 3-3 in Fig. 1. Figure 4 is a section along the line 4-4 in Fig. 1. Figure 5 is a front elevation of the grinding wheel stand with the wheel truing attachment in place. Figure 6 is a side elevation of Fig. 5. Figure 7 is a front elevation of the grinding wheel stand. Figure 8 is a plan of Fig. 7 with the valve facing attachment in place. Figure 9 is a horizontal section along the end of the grinding wheel spindle. Figure 10 is a vertical section along the line 10-10 in Fig. 9.

Similar numbers of reference refer to

the same or similar parts throughout the several views.

Referring in detail to the drawings, we have constructed our device on a regular grinding wheel stand 20 which carries the spindle 21 which, in turn, is driven through the pulley 22 coupled to the spindle 21 by the spline 23 within the pulley 22. The loose pulley 24 carries the drive belt not shown. In one end of the spindle 21 we have turned a groove 25 in which is placed the curved pieces 26 which fill the grooves. A sleeve 27 slips over this end of the shaft and completely covers the pieces 26. Screws 28 pass through the sleeve 27 and into the members 26. The projecting lugs 29 are provided with a pin 30 on which is pivoted the hand lever 31 whose end 32 is hinged to the link 33 secured by the screw 34 in the spindle journal 35. The usual grinding wheel 36, collars 37, and nut 38 are used. In some cases the nut 38 is replaced by a chuck 39 whose shank 40 is threaded to take the place of the nut 38.

A slotted bracket 41 is formed on the side of the frame 20 near the wheel 36 and to this by means of the bolt 42 are attached either the wheel truing attachment or the valve facing attachment. The truing attachment consists of an arm 43 through which the holder 44 for the diamond point 45 passes. The holder is secured by means of the set screw 46.

The facing attachment consists of an arm 47 which engages the bracket 41. Projecting from the arm 47 is a horizontal table 48 and having a bolt 49 passing through said table and having pivoted thereon a horizontal base 50 which may be indexed in any desired position by a spring-urged ball 51 within said base and which engages various countersinks in the table 48 as the base 50 is rotated on the bolt 49.

A pair of V block standards 52 are formed on the upper side of the base 50 and these are spaced to receive valves 53 ranging from the longest to the shortest valves in common use. The post 54 also rises from the base 50 and carries a screw 55 having a knurled head 56. The end of the screw 55 is provided with a point 57 to which it is loosely attached to permit the point 57 to find the center of the different sizes of valves.

A pair of slidable rods 58 pass through

the base 50 opposite the standards 52 and are provided at their lower ends with springs 59, washers 60 and nuts 61. On the upper ends of the rods 58 are the slides 62 in which journals the eccentric shaft 63 near whose ends are placed the clamps 64 having hooks 65 and stop pins 66, which pins may be threaded into the clamps 64 to produce a friction between the eccentric shaft 63 and the clamps 64. The pin 66 preferably bears against a spring which, in turn, urges a ball against the shaft. This, however, is immaterial as long as some form of friction device between the clamp and eccentric shaft is provided.

A lever 67 is secured to the shaft in a manner that when in its uppermost position it is against the valve stem, at which time the clamps 64 hold this stem down against the V blocks 52 under the tension of the springs 59. When the lever 67 is pulled outward the hooks 65 are raised to disengage them from the valve stem. Any further movement draws the hooks 65 sideways, owing to the friction between the clamp and eccentric shaft. This action, it will be understood, takes place as soon as the hooks 65 clear the valve stem, and continues until the pins 66 strike the base 50.

The valve stem is rotated by the handle 68 attached to a block 69, over which is slidably placed a V-shaped clamp 70 secured by the rivet 71 and has a stud bolt 71^a in the block 69 which passes through the V-shaped clamp 70. A spring 72 holds the V clamp 70 and the block 69 apart and the wing nut 73 on the bolt 71^a permits the clamping of the device to the valve stem end.

The operation of our device is as follows: A valve is placed in the chuck 39, as shown in Fig. 6, and the carbon removed while the valve is rotated. The valve is then placed in the V blocks 52 and the lever 67 brought to the position shown in Fig. 3. The point 57 is then placed in the valve center and the screw 55 rotated to bring the face of the valve toward the face of the grinding wheel 36, during which time the handle 68 is turned at a uniform rate of speed. This is important. The screw 55 is fed forward until the valve is properly

faced when the screw is backed off, during which time a slight pressure is exerted by the operator against the handle 68 in the direction of the screw 55, which causes the valve stem to slide in the V blocks 52 and the valve itself to clear the grinding wheel 36.

Nearly all valves are faced at 45 degrees to the axis of their stem. The base 50 is clamped when indexed by the ball 51 for this and other positions which are indexed on the table 48 by placing countersinks in the path of travel of the ball 51. Different portions of the wheel 36 may be presented to the valve 53 by operating the lever 31, and the wheel itself should be occasionally trued by replacing the facing attachment with the truing attachment and moving the wheel along against the diamond point.

If desired a belt shifter for the belt which runs on the pulleys 22 and 24 may be provided on the stand 20 instead of placing same overhead, without departing from the spirit of our invention.

We are aware that many forms of valve facing machines have been constructed in the past, we therefore intend to cover only such forms and modifications as fall fairly within the appended claim.

What we claim as new is:

The combination of a stand having a grinding wheel slidably mounted thereon with a valve facing attachment consisting of a swinging table attached to said stand; a pair of V blocks on said stand adapted to support a valve horizontally; a feed screw on said table having an extended point loosely joined to its end and adapted to engage the center of a valve; a clamp for said valve consisting of a pair of slide rods passing through said table and having springs on their lower ends and bearings on their upper ends; an eccentric shaft journaling in said bearings; and a pair of hooks mounted on said shaft adapted to clamp over the valve stem under the tension of said springs when said shaft is rotated to one of its extreme positions.

EARL G. SMITH.
ALBURT B. COMBS.
